US00D700603S

(12) **United States Design Patent**
Chen et al.

(10) **Patent No.:** US D700,603 S
(45) **Date of Patent:** ** Mar. 4, 2014

(54) **ELECTRONIC DEVICE**

(71) Applicant: **Hon Hai Precision Industry Co., Ltd.**,
New Taipei (TW)

(72) Inventors: **Hong-Sheng Chen**, New Taipei (TW);
Kuo-Chun Huang, New Taipei (TW)

(73) Assignee: **Hon Hai Precision Industry Co., Ltd.**,
New Taipei (TW)

(**) Term: **14 Years**

(21) Appl. No.: **29/440,848**

(22) Filed: **Dec. 27, 2012**

(51) LOC (10) Cl. **14-02**

(52) U.S. Cl.

USPC **D14/336; D14/374**

(57) **CLAIM**

The ornamental design for an electronic device, as shown and described.

DESCRIPTION

FIG. 1 is a perspective view of an electronic device showing our design;

FIG. 2 is a front elevational view thereof;

FIG. 3 is a rear elevational view thereof;

FIG. 4 is a left side, elevational view thereof;

FIG. 5 is a right side, elevational view thereof;

FIG. 6 is a top plan view thereof; and,

FIG. 7 is a bottom plan view thereof.

The broken lines shown are for the purpose of illustration and form no part of the claimed design.
